CASE D.

To all whom it may concern:

Be it known that I, JOHN B. ROHRER, of Philadelphia, Pennsylvania, have produced or invented a Design for a Lounge, of which the following is a specification:

The back of the lounge is partly straight and partly curved, the curved portion having at the top a scroll-like ornament, *a*. The straight portion has at each end a scroll-like ornament, *b*, and at or near the middle a knob, *d*. Both the front and back of the lounge are further ornamented with line-work and panels

In testimony whereof I have signed my name to this specification in the presence of two subscribing witnesses.
